UNITED STATES PATENT OFFICE.

CHARLES A. POINSETT, OF FLORENCE, KANSAS.

DESIGN FOR A SPOOL-STAND.

SPECIFICATION forming part of Design No. 32,862, dated June 19, 1900.

Application filed March 26, 1900. Serial No. 10,291. Term of patent 7 years.

To all whom it may concern:

Be it known that I, CHARLES A. POINSETT, a citizen of the United States, residing at Florence, in the county of Marion and State of Kansas, have invented and produced a new and original Design for Spool-Stands, of which the following is a specification, reference being had to the accompanying drawing, forming part thereof.

10 The figure is a perspective view of a spool-stand, showing my new design.

As shown in the drawing, the leading or material features of my design consist of a circular base A, a vertical standard B, extending upward from the center of said base, and a series of flat circular shelves or ledges C, parallel with each other and having their circumferential edges equidistant from the standard B. The upper surfaces of said

shelves C are each provided with upwardly-extending projections or pins D, of equal height, arranged in circles having the standard B as a center. The base A is provided on its under surface with semiglobular projections or feet E, and the upper end of the standard B has a terminal or knob F in the form of a conventionalized acorn.

Having described my invention, I claim as new and desire to secure by Letters Patent—

The design for a spool-stand, as herein shown and described.

In testimony whereof I affix my signature in the presence of two witnesses.

CHARLES A. POINSETT.

Witnesses:

G. A. SHAQUE,
B. K. GRAHAM.
